ATTORNEY

UNITED STATES PATENT OFFICE.

PATRICK J. MCINTYRE, OF CRANSTON, RHODE ISLAND, ASSIGNOR TO UNITED WIRE AND SUPPLY COMPANY, A CORPORATION OF RHODE ISLAND.

PRIMING DEVICE.

1,355,837.

Specification of Letters Patent. Patented Oct. 19, 1920.

Application filed March 17, 1920. Serial No. 366,505.

To all whom it may concern:

Be it known that I, PATRICK J. MCINTYRE, a citizen of the United States, residing at Cranston, in the county of Providence and State of Rhode Island, have invented certain new and useful Improvements in Priming Devices, of which the following is a specification.

My invention relates to priming devices for use on internal combustion engines, and its primary objects are to insure against leakage, to enable the axial passage of the body to be cleared of carbon or other accumulations by the explosion or compression of the engine charge, by a wire, or by a drill, and without detachment of the body; to permit removal of any accidental accumulation of dirt in the axial passage of the plug without dismounting the latter; to permit and facilitate disassembly of the parts, and to cheapen the construction of the device.

To the accomplishment of the foregoing and related ends, said invention consists in the means hereinafter described, and embodied in the claims.

In the accompanying drawings illustrating the principles of this invention, and which constitute a part of this specification.

Figure 1 is a side elevation of my priming device,

Fig. 2, an enlarged central vertical section of the same,

Figs. 3 and 4, similar partial sections of portions of the same showing the plug in different positions of rotation, and

Fig. 5, a section of the plug on line 5—5 of Fig. 2.

Like reference characters indicate like parts throughout the views.

In the construction illustrated 7 is the primer body with the threaded lower portion 8 adapted for insertion in a cylinder 9. In this instance the cylinder shown is of the inclined type. The upper portion of the body consists of a spherical bearing 10 having a diametrically disposed tapering seat 11, in this instance inclined to the body to the degree of inclination of the cylinder wall in which threaded portion 8 is to be inserted.

A rotatable tapering plug 12 in the seat 11 has an enlarged end portion or head 13. The opposite end portion of the plug is reduced forming a shoulder 14 and a stem 15.

Near its end the stem has a groove 17 to receive a locking plate 18 inclosed by the cap 55 19 engaged by a helical spring 20 pressing against a washer 21 abutting against the shoulder 14 and head 10.

In the head 13 is a radial hole 24 in which is mounted a tubular arm 25 terminating in 60 a hemispherical cup 26 and disposed at right angles to the plug. The center of the arm 25 constitutes a longitudinal passage 27, and near its inner end the former has diametrically opposite openings 29 in its walls. A 65 threaded opening 31 extends from the hole 24 to the periphery of the head 13 to receive a clamping screw 33 adapted to abut against the arm 25. Registering with one of the openings 29 is an axial passage 35 in the 70 plug from which extends an inclined port 36 adapted to register with an axial passage extending throughout the body. The portion of the latter passage below the plug is identified as 37; the portion thereof above 75 the plug, by the numeral 38. The latter portion forms an opening in the periphery of the bearing portion 10 of the body. In one position of rotation only of the plug 12 does the port 36 register with the portion 37 of 80 the body passage, namely in the position of priming shown in Figs. 1 and 2. In no position of rotation can the port 36 communicate with the portion 38 of the body passage. Hence no leakage of oil is possible. 85

At an angle of ninety degrees from the port, measured on the periphery of the plug, is a transversely disposed longitudinally inclined passage 40 through the plug communicating with the port 36 at the merging 90 point of the port with the passage 35. In only one position of rotation of the plug does the passage 40 register with the body passage 37, 38, namely in one horizontal position of the arm 25. This position is 95 shown in Fig. 3, wherein the parts are disposed for cleaning. Thus disposed, a continuous passage is afforded from the interior of the engine cylinder to the atmosphere whereby the passage 37 may be 100 cleared; or a wire or drill is receivable in the latter passage for cleaning without detaching the priming device from the cylinder.

In Fig. 4 is shown the position of the parts when the arm 25 is depressed into normal or non-cleaning and non-priming posi-

tion. The valve ports or passages are in this position protected from all ingress of foreign elements.

If any dirt accumulates in the passage 35 it is accessible by removing the threaded plug 33 and inserting the cleaning implement through the opening 31. The removal of the member 33 also permits the withdrawal of the arm 25 when desired.

10 The disposition of the various passages facilitates the drilling thereof and lessens the cost of construction.

The inclined position of the plug 12 relatively to the body 7 insures a vertical position of the cup 26 when the plug is mounted 15 in the wall of an inclined cylinder.

It is to be understood that the invention is not limited to the specific form herein illustrated and described but may be embodied 20 in other forms without departure from its spirit as defined by the following claims.

I claim:—

1. In a priming device, a body provided 25 with a longitudinal passage throughout its length, a plug valve rotatably mounted in the body provided with a longitudinal passage, and with a port registerable with the first passage, and with a transverse passage extending through the valve and registerable 30 with the first passage, an arm on the valve, and a cup on the arm, said arm being provided with a passage communicating with the cup and with the second longitudinal passage.

35 2. In a priming device, a body provided with a longitudinal passage throughout its length, a plug valve rotatably mounted in the body intersecting the passage and provided with an axial passage, and with a port 40 registerable with the first passage, and with a transverse passage communicating with the port and registerable with the first passage, an arm on the plug, and a cup on the

arm, said arm being provided with a passage communicating with the cup and with 45 the axial passage.

3. In a priming device, a body provided with a longitudinal passage throughout its length, a plug valve rotatably mounted in the body and disposed at an inclination to 50 the body provided with an axial passage and with an inclined port registerable with the first passage, and with a transversely disposed longitudinally inclined passage extending through the valve and merging with 55 the port and the axial passage and registerable with the first passage, an arm on the valve, and a cup on the arm, said arm being provided with a passage communicating with the cup and with the axial passage. 60

4. In a priming device, a body provided with a longitudinal passage, a plug valve rotatably mounted in the body provided with an axial passage, a port registerable with the first passage, a radial hole, and a 65 threaded opening extending to the hole in alignment with the axial passage, a tubular arm in the hole provided with diametrically opposite openings adapted to register with the axial passage and with the threaded 70 opening, a cup on the arm, and a clamping screw in the threaded opening.

5. In a priming device, a body provided with a longitudinal passage, a plug valve rotatably mounted in the body provided 75 with an axial passage, a port registerable with the first passage, a radial hole, and a threaded opening extending to the hole in alignment with the axial passage, a tubular arm in the hole provided with a lateral opening 80 adapted to register with the axial passage, a cup on the arm, and a clamping screw in the threaded opening.

In testimony whereof I have affixed my signature.

PATRICK J. McINTYRE.
